UNITED STATES PATENT OFFICE.

AUGUSTE BONNART, OF PHILADELPHIA, PENNSYLVANIA.

REVERSING MEANS FOR INTERNAL-COMBUSTION ENGINES.

1,224,839.

Specification of Letters Patent.

Patented May 1, 1917.

Application filed December 13, 1916. Serial No. 136,727.

To all whom it may concern:

Be it known that I, AUGUSTE BONNART, a citizen of the Republic of France, residing at Philadelphia, in the county of Philadelphia and State of Pennsylvania, have invented new and useful Improvements in Reversing Means for Internal-Combustion Engines, of which the following is a specification.

10 This invention relates to reversing means for internal combustion engines, the objects in view being to provide means for changing the timing of the admission of fuel to the combustion chamber of the engine so that an explosion may be obtained before the piston completes its return stroke, thereby interrupting said return movement and causing the piston to be driven in the reverse direction, thereby imparting a reverse 20 rotation to the engine shaft.

A further object of the invention is to provide in conjunction with a fuel injecting pump, pump operating means actuated by the engine shaft, and manually controlled means for temporarily varying the action of the pump operating means for the purpose of causing the pump to inject the fuel to the combustion chamber of the cylinder at a time when the piston is between the two 30 limits of its reciprocatory movement with the result that the piston movement is arrested at such point and the piston is driven in the reverse direction, thereby reversing the direction of rotation of the engine shaft.

35 With the above and other objects in view, the invention consists in the novel construction, combination and arrangement of parts herein described, illustrated and claimed.

In the accompanying drawings:—

40 Figure 1 is an elevation showing an internal combustion engine equipped with the improved reversing mechanism.

Fig. 2 is an enlarged section on the line 2—2 of Fig. 1.

45 Fig. 3 is a fragmentary section taken diametrically of the engine shaft which is, however, shown in elevation, said section passing through the eccentric and transmission member.

50 Fig. 4 is an enlarged longitudinal section through the fuel pump, showing also the means for adjusting the throw of the pump plunger.

Fig. 5 is a fragmentary elevation of the governor mechanism. 55

Fig. 6 is a fragmentary section on the line 6—6 of Fig. 4.

Fig. 7, 8 and 9 are diagrammatic views illustrating the operation of the pump actuating mechanism. 60

Referring to the drawings 1 designates the base of an internal combustion engine, 2 the engine shaft which is mounted for rotation in the base, 3 the engine cylinder and 4 the fuel feed pipe which is shown as leading into the head 5 of the cylinder 3 and having associated therewith a pump casing 6 hereinafter more particularly described and serving to force the fuel through the pipe 4 into the combustion chamber of the cylinder. 65

Referring now particularly to Fig. 4, which shows the mechanism of the fuel injecting pump, the pump casing 6 contains a fuel inlet check valve 7 and a fuel outlet back pressure check valve 8, said valves being arranged at opposite sides of a chamber 9 in which reciprocates a pump plunger 10. The working stroke of the pump plunger 10 is effected by a tappet 11 in turn actuated by a rocking lever 12 the actuating means 75 for which will be hereinafter described. The tappet 11 is provided with an enlarged cylindrical portion or head 13 the extremity of which is rounded and is acted upon by the lever 12. The other end of the tappet 11 reciprocates back and forth in an adjustable stop 14 of tubular formation as shown in Fig. 4, said stop 14 also receiving and admitting of the reciprocatory movement of the adjacent end of the pump plunger 10, 80 the return movement of the plunger 10 being limited by a stop collar 15 thereon and the return movement of the plunger 10 being effected by means of a spring 16 which is coiled around the plunger 10 and interposed between the shoulder or collar 15 and a stationary shoulder 17 which is shown as 85

consisting of the gland of a stuffing box 18 through which the pump plunger 10 reciprocates, said stuffing box being carried by the 100 body 19 of the chamber in which the pump plunger 10 reciprocates. The return movement of the tappet 11 is effected by means of a spring 20 which is interposed between a shoulder 21 of the tappet and the adjacent 105 end of the adjustable stop 14. The stop 14

is provided with a longitudinal key-way or groove 22 which receives the inner extremity of a key 23 shown in the form of a screw having a reduced inner extremity which fits 5 in the groove 22 and permits the stop 14 to slide longitudinally but prevents rotative movement thereof.

The means for adjusting the stop 14 comprises a gear 24 which meshes with a rack 10 face 25 on the stop 14. The gear 24 is mounted on a shaft 26 journaled in a bearing 27 shown as formed integrally with the casing 6, the shaft 26 having fast thereon a sector gear 28 the teeth of which mesh 15 with a worm 29 on a countershaft 30 actuated by the engine shaft 2 as will appear. The sector gear 28 has an arm 31 adapted to contact with an adjustable limiting member 32 shown in the form of a screw 20 having a threaded engagement with a lug 33 or its equivalent shown as projecting from the wall of the cylinder 3. By adjusting the member 32, the throw of the sector gear 24, and therefore the throw of 25 the adjustable stop 14 may be restricted within certain limits. To initially prime the engine, a manually operable priming member 34 in the form of a lever is mounted 30 pivotally at 35 on the pump casing 6 and one arm of said lever or priming member works through a slot 36 in the pump casing and engages the collar 15 on the pump plunger 10. This enables the operator to 35 inject a sufficient quantity of fuel into the engine for the purpose of starting the same before the pump is actuated by the operating means partly described hereinabove. It will be observed that when the adjustable stop 14 is moved to the right in Fig. 4, it 40 will be followed by the plunger 10 due to the expansion of the plunger return spring 16. Consequently a longer stroke will be imparted to the plunger 10 by the tappet 11. On the other hand when the stop 14 is shifted to the left in Fig. 4, it will carry 45 with it the plunger 10 and this will shorten the throw of the plunger. The throw of the tappet 11 will not be changed by the shifting of the stop 14 but the throw of 50 the pump plunger will be changed and thereby a greater or lesser amount of fuel will be forced to the combustion chamber of the engine.

The means for controlling the movement 55 of the adjustable stop 14 is best illustrated in Fig. 5, the shaft 2 having mounted thereon a carrier or bracket 37 having a plurality of arms 38 to which weighted centrifugal governor arms 39 are connected 60 by pivots 40, the governor arms being connected by a yieldable member 41 shown in the form of a contractile spring which resists the outward movement of the governor arms as they are rapidly carried around by 65 the carrier 37 which is fast on the engine

shaft 2. Slidingly mounted on but rotating with the shaft 2 is a sleeve 42 having two motion transmitting wheels 43 and 44 fast thereon and movable alternately into and out of engagement with another wheel 45 70 on the adjacent end of the countershaft 30 hereinabove referred to. The sleeve 42 is formed with a groove 46 which is engaged by fingers 47 of the governor arms 39. By the operation of the governor mechanism 75 just described, as the speed of the shaft becomes excessive, the wheel 43 is moved into driving engagement with the wheel 45 thereby turning the countershaft in the proper direction to reduce the working 80 stroke of the fuel pump plunger. When the speed decreases below a predetermined point, the governor mechanism shifts the wheel 44 into engagement with the wheel 45 thereby increasing the throw of the 85 pump plunger, which increases or decreases when the throw of the pump plunger is effected by the shifting of the stop 14 in the manner above explained.

Referring now to Fig. 1, the rocking 90 lever 12, is shown as connected by means of a link 48 to an eccentric rod 49 which is fulcrumed so as to function also as a lever. The rod 49 is fixedly connected at one end to an eccentric strap 50 which encircles an eccentric 51 normally loose in relation to the engine shaft 2. Fixedly mounted on the engine shaft 2 is a motion transmitting member 52 having a disk shaped body portion and shoulders 53 and 54, shown as having concaved faces and adapted to engage, one at a time, a shoulder 55 on the eccentric 51, the shoulder 55 being shown in the form of a pin or stud projecting from one face of the eccentric. At this point it may be noted that as the motion transmitting member 52 is fast on the engine shaft 2, it acts upon the shoulder 55 to take up and drive the eccentric 51 as one or the other of the shoulders 53 and 54 must engage the shoulder 55, in accordance with the direction in which the engine shaft 22 is rotating. When the direction of rotation is changed, there will be an interval of disengagement between the member 52 and the eccentric 51 equal to the greatest distance between the shoulders 53 and 54, that is while the shoulder 55 is traveling around the body portion of the member 52 in moving from one of the shoulders 53 to the other shoulder 54 or vice versa. This is the means by which the time of movement of the fuel pump plunger is changed so as to inject the fuel into the combustion chamber and allow the same to be ignited by means of a hot ignition tube, before the piston has reached the limit of its return stroke, the explosion at such time driving the piston back and thereby reversing the rotation of the en- 110 115 120 125 130

gine shaft. 56 designates a collar on the engine shaft 2 behind the eccentric 51 and the hub 57 of the member 52, on which hub the eccentric 51 is journaled, as shown in Fig. 3.

5 The reversing lever 58 is shown as of the thumb latch type, said lever being fulcrumed on a bracket 59 shown as secured to the engine base, the latch 60 of the reversing lever 58 is adapted to be placed in engagement with any one of the three notches *a*, *b* and *c* in a rack 61 also shown as fastened to the engine base 1. Referring to Figs. 1 and 2, the reversing lever 58 carries 10 a laterally projecting journal or stud shaft 62 upon which is mounted one end of a link 63 the other end of which carries a pin 64 by which it is pivotally connected to the eccentric rod 49 as best illustrated in Fig. 2. 15 The outer end of the shaft 62 has connected thereto a swinging support or yoke 65 the opposite end of which is pivotally connected to the bracket 59 above referred to. When the lever 58 is moved from the notch *a* to 20 the notch *c* or vice-versa, the pivot 64 is shifted to one or the other of the two positions shown in the diagrams Figs. 7 and 8 thereby causing the pivot 66 to describe 25 one or the other of the ellipsoidal or orbital paths shown in said diagrams. When the latch 60 is in the intermediate notch *b*, the pivot 66 describes an approximately circular path as shown by dotted lines in said diagrams. In other words when the latch 60 30 is in the notch *c*, the pivot 64 moves in the arcuate path designated by the line *d* in Fig. 7 while the pivot 66 describes the full line ellipsoidal path *e* of the same figure. When the latch 66 occupies the notch *a*, the pivot 35 40 45 50 55 60 65 70 75 80 85 90 95 100 105 110 115 120 125 130 135 140 145 150 155 160 165 170 175 180 185 190 195 200 205 210 215 220 225 230 the same direction but when the piston has completed about one-half of its return stroke indicated by the position *l* in Fig. 9, the fuel pump has just completed a full working stroke as indicated by the position of the projection 55 on the line *m n* of Fig. 9. Then the explosion of the charge acts against the piston before it reaches the end of its return stroke and drives the same 10 backwardly thereby reversing the direction of rotation of the engine shaft. The member 52 is thus caused to turn in the reverse direction of the engine shaft thereby bringing said member 52 into the relation to the 15 projection 55 shown in Fig. 8 wherein the piston has reached the limit of its return stroke as indicated by the position *l* while the projection 53 is on the line *m n* of Fig. 8. It will be observed that, with the parts in 20 this position, the fuel pump has just completed its working stroke. Thus in both Figs. 7 and 8, which show the position of the parts when the lever 58 is in the position *a* and in the position *c*, the fuel pump completes 25 its working stroke as the piston reaches the limit of its return movement or the position where ignition takes place. By moving the lever 58 to the position *b*, the operation of the fuel pump is stopped and 30 consequently the engine terminates its operation as it can no longer operate without the fuel being forced into the combustion chamber thereof.

From the foregoing description taken in 35 connection with the accompanying drawings it will now be understood that the reversal of direction of rotation of the engine shaft is brought about by injecting the fuel into the combustion chamber of the engine at an 40 intermediate point in the length of the working stroke of the piston causing the piston to be driven backwardly toward the engine shaft before it has reached the end of its normal return stroke. I do not desire to 45 be restricted to the particular embodiment of the invention as herein above described in the accompanying drawings. These drawings merely illustrate one way of carrying out the invention and utilizing the same in 50 connection with an internal combustion engine and particularly an engine adapted to operate with fuel of a low specific gravity, in which a hot ignition tube or the equivalent thereof is used for igniting the fuel. It 55 will therefore be apparent that the mechanism particularly described and shown is susceptible of changes in the form, proportion and minor details of construction which may accordingly be resorted to without departing from the principle or sacrificing any of the advantages of the invention.

I claim:

1. The combination with an internal combustion engine, of a fuel injecting pump for 65 supplying fuel under pressure to the com-

bustion chamber of the engine, pump actuating means operated by the engine shaft, means for changing the timing of the working stroke of the pump in relation to the working stroke of the engine piston, the 70 last named means comprising an eccentric normally loose in relation to the engine shaft, an eccentric rod actuated by said eccentric, and a motion transmitting member fast on the engine shaft and adapted to engage and disengage said eccentric. 75

2. The combination with an internal combustion engine, of a fuel injecting pump for supplying fuel under pressure to the combustion chamber of the engine, pump actuating means operated by the engine shaft, means for changing the timing of the working stroke of the pump in relation to the working stroke of the engine piston, the last named means comprising an eccentric normally loose in relation to the engine shaft, an eccentric rod actuated by said eccentric, and a motion transmitting member fast on the engine shaft and adapted to engage and disengage said eccentric, said motion transmitting member and said eccentric having a certain amount of free rotative movement in 80 relation to each other. 85

3. The combination with an internal combustion engine, of a fuel injecting pump for supplying fuel under pressure to the combustion chamber of the engine, pump actuating means operated by the engine shaft, means for changing the timing of the working stroke of the pump in relation to the working stroke of the engine piston, the last named means comprising an eccentric normally loose in relation to the engine shaft, an eccentric rod actuated by said eccentric, and a motion transmitting member fast on the engine shaft and adapted to engage and disengage said eccentric, said motion transmitting member having a plurality of shoulders in spaced relation to each other and adapted one at a time to engage a shoulder 100 on said eccentric. 105

4. The combination with an internal combustion engine, of a fuel injecting pump for supplying fuel under pressure to the combustion chamber of the engine, pump actuating means operated by the engine shaft, means for changing the timing of the working stroke of the pump in relation to the working stroke of the engine piston, the last named means comprising an eccentric normally loose in relation to the engine shaft, an eccentric rod actuated by said eccentric, a motion transmitting member fast on the engine shaft and adapted to engage and disengage said eccentric, said motion transmitting member having shoulders in spaced relation to each other, and a shoulder on said eccentric adapted to be engaged by either one of the shoulders on the motion transmitting member and capable of movement 115 120 125 130

from one shoulder to the other without affecting the motion transmitting member.

5. The combination with an internal combustion engine, of a fuel injecting pump for supplying fuel under pressure to the combustion chamber of the engine, pump actuating means operated by the engine shaft, means for changing the timing of the working stroke of the pump in relation to the 10 working stroke of the engine piston, the last named means comprising an eccentric normally loose in relation to the engine shaft, an eccentric rod actuated by said eccentric, a motion transmitting member fast 15 on the engine shaft and adapted to engage and disengage said eccentric, a fulcrum pin for said eccentric rod, and means for shifting said fulcrum pin to vary the effective throw of the pump plunger.
- 20 6. The combination with an internal com-

bustion engine, of a fuel injecting pump for supplying fuel under pressure to the combustion chamber of the engine, pump actuating means operated by the engine shaft, means for changing the timing of the working stroke of the pump in relation to the 25 working stroke of the engine piston, the last named means comprising an eccentric normally loose in relation to the engine shaft, an eccentric rod actuated by said eccentric, 30 a motion transmitting member fast on the engine shaft and adapted to engage and disengage said eccentric, a fulcrum pin for said eccentric rod, and manually controlled means for shifting said fulcrum pin to vary 35 the working radius of said eccentric rod and thereby render the pump effective or ineffective.

In testimony whereof I affix my signature.
AUGUSTE BONNART.
